[57] CLAIM

The ornamental design for a battery case for diving use, as shown and described.

DESCRIPTION

FIG. 1 is a perspective view of a battery case for diving use. The broken line showing of the belt in FIG. 1 is included for the purpose of illustrating environmental structure only, and forms no part of the claimed design; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; and, FIG. 7 is a bottom plan view thereof.
